(57) **CLAIM**

The ornamental design for a molded case for an electronic device, as shown and described.

DESCRIPTION

FIG. 1 is a front-elevational view of a molded case for an electronic device showing our new invention;

FIG. 2 is a rear-elevational view thereof;

FIG. 3 is a top-perspective view thereof;

FIG. 4 is a bottom-perspective view thereof;

FIG. 5 is a right side-elevational view thereof, with the left side being a mirror image thereof;

FIG. 6 is a front-perspective view thereof; and,

FIG. 7 is a rear-perspective view thereof.
